UNITED STATES PATENT OFFICE.

JOSEPH E. CORNACCHIONE, NOW BY JUDICIAL CHANGE OF NAME JOSEPH ETTOR CORNACCHIONE CONRACE, OF NEW YORK, N. Y.

TYPEWRITER-PAPER STOP.

Application filed September 4, 1925. Serial No. 54,483.

My invention relates to an automatic writing stop for use in typewriting.

The main object is to provide a simple, practical, and inexpensive automatic means 5 to enable anyone using a typewriter to immediately ascertain when the writing end of the sheet being typewritten has been reached.

Another object is to save as much of the 10 platen surface as possible by having an extra thickness of material adjacent the platen.

Another object is to provide means of advertising which will be constantly brought 15 to the attention of typists.

Fig. 1 is a transverse sectional view of part of a typewriting machine showing the relative positions of a bundle of typewriting sheets and carbon, together with a device 20 embodying one form of my invention, the writing having gone about three-quarters of the length of the sheet.

Fig. 2 is a perspective view of the preferred form of my invention, the line across 25 the width of the sheet indicating an extended fold.

Fig. 3 is a perspective view of a modification of my invention showing an expandable fold.

30 Fig. 4 is a plan view of another modification of my invention showing the sides stiffened.

Fig. 5 is a fragmentary plan view of my invention showing one form of longitudinal 35 extension means.

Fig. 6 is a sectional view on the plane of the line 6—6 of Fig. 5.

Fig. 7 is a perspective view of a further 40 modification of my invention.

It usually requires two operations for a typist to ascertain the writing end of a sheet. He must look at the sheet to see how far 45 he has written and how much further he can write, (the platen is usually twirled) and then re-locate his place in the copy or notes to go on writing. Sometimes it is necessary to repeat these operations, the typist's "guess" not being quite right the first time.

50 I propose to overcome these difficulties by the use of a special sheet having a projection adapted to abut or stop and grip a part of the typewriting machine. The paper to be written on is fed into the machine with this sheet and the stop is adjusted to pre-

vent, automatically, the feeding of the paper, just before the end of the paper is reached. By automatic is meant means which will tell the typist, without any effort on his part, when the writing end of 60 the sheet in question has been reached.

My invention consists of a flexible sheet or base 10 having an abutment or projection, herein called a stop, 11, secured thereto in any suitable manner. In my preferred 65 form the base 10 consists of a sheet of material of the size and consistency of typewriting paper except that it should be somewhat greater in length than the size of the particular paper being written on at the 70 time. I do not, of course, wish to limit myself to any particular consistency or grade of material, for any that is suitable for this purpose will do. In the event, however, that very thin or flimsy material is used 75 as the base, which would be preferably in manifold work, it may be reinforced in order that it may be more readily aligned with the other sheets to be typewritten before inserting the package of sheets in the 80 machine. For instance, the edge or edges 12 of the base 10 to any desired width may be stiffened in any suitable manner, such as being impregnated with a stiffening compound, or affixing or folding another layer 85 of material so that the base will not crumple up when being aligned with the other sheets.

The sheet 10 may be of heavier card board when only a few copies are to be struck at once and in this case affording 90 protection to the platen 13.

The stop 11 is an abutment or projection secured to the base 10 and of such size, shape and material that it cannot pass through that part of the typewriting machine between the platen 13 and the paper feed rolls 14 after the stop has reached the platen. In my preferred form, the stop 11 may be composed of material whose surface, when abutting against the platen surface of a typewriting machine, will grip with said platen surface, making it impossible for the two surfaces to slide on each other, and thus prevent feeding. I have found best results to be had from a stop 105 composed of yielding material, such as rubber, and of the shape shown in Figs. 1 and 2. The size of the stop may be varied, and it may extend either partially or wholly 110 across the width of the base.

The stop 11 may be attached to the base 10 in any suitable manner, either permanently or temporarily. I preferably use glue for permanent attachment. Wire rivets, or the like, of course, could be also used.

The point of attachment should be at a point on the base somewhat beyond where the bottom end of the sheet being typewritten would fall, the upper edges of the sheet 10 and base being aligned. The exact location, of course, would be determined by the amount of margin desired at the end of the typewritten sheet.

As a modification of my invention, when used in writing with various sizes of paper and also in the event that it is desired to write a few more lines on the sheet while it is still in the typewriter but after the device has stopped the feed, I may provide a 20 double or bellows-like fold 15 at one end of the base 10 so that the portion of the base to which the stop 11 is attached may be unfolded and extended outwardly, the position of the stop then being beyond the line of writing.

Another modification would be to have the stop adjustable or detachable, inserting it into an opening or openings 16 in the base so as to provide a flexible longitudinal 30 margin. Graduations 17 could be provided on the base 10 so that the stop could be attached at the proper place for any size sheet; the graduations may, if desired, correspond to the size, in inches, of the particular length of sheet being used. Any proper means, such as button 18, could be provided for attaching and detaching the stop of the base.

A further modification would be to have the graduations 17 shown at the end of the base opposite the stop 11, the stop being permanently attached, so that the top edge of the sheet or sheets to be typewritten could be aligned inwardly of the base to provide 45 for any desired margin.

Another further modification would be to have the upper part 19 of the stop detachable, and movable longitudinally of its base 20; thus creating a flexible margin in proportion to the longitudinal movement provided. The stop 19 may be adjusted longitudinally of the support 20 in the opening or 50 openings 22 in any suitable manner, for instance by the engagement of pins 21 with notches 23.

In order to assist in aligning and inserting the sheets into the typewriter, I may provide an inward fold 24 on the base 10 inside of which fold the sheets would be inserted, thus providing for only one edge to be inserted into the machine instead of a number of edges corresponding to the number of copies being made; the result being practically perfect alignment.

I may also provide a suitable opening

or openings 25 at any point in the base 10 for conveniently hanging up the device when not in use.

In employing my invention, the sheet or sheets 26 to the typewritten are assembled in 70 the usual manner, my device being aligned and placed as the last sheet of the package so that the stop 11 faces the platen 13 when being inserted into the machine. The typist commences to write and the device is fed 75 simultaneously with the sheets.

When the writing end of the sheet has been reached, the stop 11 will abut against the platen surface 13 and grip with it so that the platen cannot be fed forwardly, the 80 stop being too large to pass through the paper feed. When the typist attempts to use the line spacer to feed into the next line after the stop has abutted against the platen, he finds that he cannot do so, the 85 platen and stop gripping tightly together, and not only stopping the feeding but also the normally smooth operation of pushing the carriage of the machine back to the right, this operation being usually simultaneous with the spacing or feeding.

This gripping action is so decided and noticeable to the typist in comparison with the normally smooth operation that he knows immediately that the writing end of the 95 sheet has been reached. In fact on most standard typewriting machines the device not only stops the feeding of the paper but interferes with the movement of the carriage as well, until the line spacer is released.

In taking the package of sheets and the device from the machine, the sheets are pulled forwardly and the device in the opposite direction. In my preferred form I 105 provide a longitudinal projection 27 on the base 11 to be gripped by the typist in taking the device from the machine.

The space on the base may be used as an advertising medium, or for any other 110 purpose for which it may be adaptable.

I claim:—

1. A typewriter paper stop comprising a flexible backing sheet adapted to be assembled with the writing paper in the platen of the machine and having a projection serving to wedge behind the platen to prevent the feeding of the paper.

2. A construction of the character described in claim 1 in which at least a part of the projection is formed of yielding material such as soft rubber.

3. A typewriter paper stop comprising a flexible backing sheet adapted to be assembled with writing paper on the platen of the machine and having a wedge-shaped soft rubber projection secured to one surface of said sheet near one end.

4. A construction of the character set forth in claim 1 in which at least a part of

the projection is adjustable longitudinally with respect to the backing sheet.

5. A typewriter paper stop comprising a flexible backing sheet, a projecting member secured thereto near one end for wedging behind a platen, said sheet extending beyond said projecting member to serve as a handle for withdrawing the sheet.

6. A typewriter paper stop comprising a flexible backing sheet, a projection stop member secured thereto near one end, said sheet having a pocket near the other end to engage one end of a package of sheets to be inserted in a typewriting machine.

15. 7. A typewriter paper stop consisting of a flexible backing sheet adapted to be assembled in the machine with the paper to be written upon and having a projecting stop near one end for engaging the platen to stop

the feeding of the sheet and the paper, and 20 having a series of indicating marks near the other end of the sheet for indicating the proper position of the paper with respect to the sheet to ensure stopping the writing of the machine when the paper has passed 25 through the machine the desired distance.

8. In a typewriter paper stop the combination of a platen, an introductory paper guide and feed roller, a stop member, and a member connected to the stop member and 30 movable with the rotation of the platen for bringing said stop member into position between said platen on the one side and said introductory paper guide and feed roller on the other side to stop the rotation of the 35 platen.

JOSEPH E. CORNACCHIONE.
